UNITED STATES PATENT OFFICE

163,833

KITCHEN CABINET PULL

Roy A. Stone, Rockford, Ill., assignor to National Lock Company, Rockford, Ill., a corporation of Delaware

Application March 7, 1950, Serial No. 8,373

Term of patent 7 years

(Cl. D10—8)

To all whom it may concern:

Be it known that I, Roy A. Stone, a citizen of the United States, and a resident of Rockford, in the county of Winnebago and State of Illinois, have invented a new, original, and ornamental Design for Kitchen Cabinet Pull, of which the following is a specification, reference being had to the accompanying drawing, forming part hereof.

In the drawing:

Fig. 1 is a front elevation of a kitchen cabinet pull embodying my new design;

Fig. 2 is a plan view thereof;

Fig. 3 is a view looking upwardly at Fig. 1;

Fig. 4 is a rear elevation of the pull shown in Fig. 1;

Fig. 5 is an end elevation thereof; and

Fig. 6 is a sectional view on the line 6—6 of Fig. 4.

I claim:

The ornamental design for a kitchen cabinet pull, substantially as shown.

ROY A. STONE.
